6, 1946, Serial No. 652,262

9 Claims. (Cl. 101—144)

1

This application is a division of my copending application No. 573,280 filed January 17, 1945 for a Printing Machine.

The invention of this application relates to a rotary printing machine operating on the planographic principle. The general object of the invention is to provide such a machine which shall have means for transferring an image from a master sheet to a transfer blanket in an efficient manner, and which shall reproduce on the transfer blanket an image corresponding accurately with the image on the master sheet, so that an accurate impression will be made on the paper printed.

A more particular object of the invention is to control the approach of the master drum carrying the image to the offset drum carrying the transfer blanket so that actual contact of the two drums shall start in advance of the presentation of the image to the blanket, and thus the actual transfer of the image shall always be by rolling contact, thereby avoiding the smudging or distortion of the transferred image likely to result from a radial or blow contact.

Still more particularly, my invention provides means for causing a master drum to contact with the offset drum only when a gap in one of the drums faces the other drum.

The drawings illustrate a preferred embodiment of my invention. In these drawings, Fig. 1 is a vertical section through the machine, the offset blanket being illustrated merely in conventional form; Fig. 2 is a side elevation of latching mechanism for retaining the offset drum in coaction with the master drum and platen but allowing its immediate separation from both such members, this view showing the drums in their separated or inactive position; Fig. 3 is a view of the same parts with the latch in another position and the drums in their coacting position; Fig. 4 is a side elevation of certain parts of the machine outside of the right hand frame plate and in plane parallel with Fig. 1; Fig. 5 is a section immediately broken away through the offset drum on a plane indicated by the line 5—5 on Fig. 1; Fig. 6 is a sectional elevation on a plane parallel with Figs. 1 and 4 showing some of the gearing employed in the machine.

I will first describe briefly the general characteristics of the complete printing machine indicated in the drawings.

In Fig. 5, there is shown two spaced vertical frame plates 10 and 11 parallel with each other which together with bracing cross rods, constitute the main frame of the machine. Plate 10

2

also appears in Fig. 4 and the plate 11 in Figs. 1 and 6. Ordinarily these frame plates and the machine carried thereby rest on a suitable base or stand indicated at 15 in Fig. 1. This stand may house a driving motor 16 connected by a belt 17 with a pulley 18 of the printing machine.

The printing machine includes a master sheet carrying drum 20, an offset drum 30 and a platen 40 all suitably mounted between the two plates 10 and 11. Between these plates also is an inking mechanism 50 adapted to deliver ink to the master sheet 22 on the drum 20, and a normally acting ink repellent applying mechanism 60 acting on a region of the master sheet in advance of the inking mechanism.

Between the frame plates 10 and 11, there is also mounted the control mechanism 90 for the manual paper feed and a projecting paper support 97, and behind the platen there is provided means for holding a removable receiving tray 98. Various mechanisms hereinafter described are mounted on the exterior of the two frame plates 10 and 11 and are shielded by side cover plates 12. Substantially all of the parts of the machine between the frame plates may be covered by a suitable cover which is removed when the machine is operated. Such removable cover is indicated at 19 as extending over the entire top of the machine and downwardly beyond each end thereof to regions a short distance above the paper support and the inking fountain.

The master drum 20 is provided with an axially extending recess 23 in which is mounted an attaching means, generally indicated at 24, for attaching a printing plate to the drum.

The master drum 20 is rigidly mounted on a shaft 21, the ends of which are preferably journaled in eccentric bushings 26 mounted in the frame plates 10 and 11, to allow accurate alignment. The offset drum 30 is rotatably mounted on an eccentric central portion of a shaft 31 which is mounted in the two frame plates in a manner capable of a partial rotation, by which the position of the offset blanket 33 is adjusted with reference to both the master sheet and the platen as hereinafter described.

The platen 40 is rotatably mounted on an eccentric intermediate portion of a shaft 41, the axial end portions of which are mounted in bearings carried by a yoke 42 pivoted to the plates 10 and 11 at 43 and spring pressed upwardly by a pair of spring units 45 (one of which is shown in Fig. 1) which act against the transverse portion of the yoke distant from the pivot. These spring units maintain proper yielding pressure between

the platen and the offset cylinder during the operation of the machine.

Each unit 45 includes a spring 44 which bears at its lower end against a fixed cross bar 46 carried by the two frame plates 10 and 11. At their upper ends each spring acts against an adjustable stop 47 on a screw 48, the upper end of which is anchored to the yoke and the lower end of which passes through the cross bar 46, and is provided with a nut 49. These nuts provide adjustable limits for the upward movement of the platen yoke.

As shown, the inking mechanism 50 comprises a fountain 51 adapted to contain ink, a fountain roller 52 therein, a swinging ductor roller 53, a longitudinally reciprocable distributing roller 54, and a form roller 55. The latter coacts with the master sheet 22 on the drum 20 and with the distributing roll 54.

The form roll 55 may be manually separated from the master sheet 22 to facilitate the initial application of ink-repellent thereto, as well as to facilitate the substitution of one master sheet for another. As illustrated the form roll 55 is mounted between a pair of plates 56 pivoted to the respective frame plates 10 and 11 and drawn by springs 57 toward the master sheet under the control of an adjustable stop screw 58. A suitable cam rod 59 rotatively mounted in the frame plates is adapted to be turned by the operation of a hand lever 59a, Fig. 4, to cam the plates 56 in a direction to separate the form roll from the drum.

The normal ink repellent applicator mechanism which acts on the master sheet during each revolution of the master drum, as illustrated in Fig. 1, comprises a trough 61 adapted to contain a liquid ink repellent, a fountain roll 62 immersed therein, a swinging ductor roll 63 and an absorbent form roll 64. The form roll is mounted in a pair of pivoted end bars 65 which are drawn toward the master drum 20 by springs 66 under the control of adjustable stop screws 67. The ductor roll 63 oscillates between the fountain roll 62 and the form roll 64 to deliver repellent to the master sheet.

The two ductor rolls 53 and 63, as well as the fountain rolls 52 and 62, for the ink and repellent respectively are operated at the same time by a single cam 70 secured to the offset drum 30, which is driven by suitable gearing as hereinafter explained. This cam 70 acts against a roller 71 (Fig. 4) on a lever 29 secured to a stub shaft 73 journaled in the frame plate 10. A second lever 72 is secured intermediate its ends to the stub shaft 73 and is connected by a link 74 with mechanism not shown for periodically turning the ink fountain roll 52. The lever 72, also by mechanism not shown, actuates the repellent ductor.

The offset drum may be released from both the master drum and the platen by turning the eccentric shaft 31 on which the offset drum is mounted. This shaft is normally in the position shown in Figs. 1 and 3. As illustrated in Fig. 3, a cam 34 is secured to the shaft 31 and a spring 39 is connected between this cam and the frame plate 10 to swing the shaft in a counter-clockwise direction and thereby move the offset drum away from both the platen and the master drum. Normally the swinging of the shaft is prevented by a latch 37 which is retained in engagement with a tooth 36 on the cam by a spring 35.

The latch 37 has a suitable lateral extension 38 projecting through an opening in the cover on that side, so that whenever desired the latch may be withdrawn from the cam 34 by manual pres-

sure against the extension 38. This releases the cam 34 and permits the spring 39 to swing the offset drum shaft and bring the offset drum to its inactive position, shown in Fig. 2. When it is desired to restore the offset drum to its active position, the operator grasps a handle or knob 32 which is secured to the shaft 31, and turns the same in a clockwise direction until the cam 34 is reengaged by the latch 37. A portion of the handle is shown at 32 in Fig. 5, and it is indicated in broken lines in Fig. 4.

Coming now to the particular portion of the machine with which the present invention is concerned, I may repeat that it is an important feature of this invention that the master drum and the offset drum be brought into position to contact with each other only at a time when a gap in one of the drums is juxtaposed to the other drum, because this avoids any blow or radial impact on the image, which might tend to blur the reproduction. In the embodiment shown, the gap referred to is on the master drum. By starting the coaction when the gap on the master drum is opposite the offset drum the image is never submitted to other pressure than a rolling action.

The result above noted is accomplished by the mechanism shown in Figs. 2 and 3. It will be there seen that the cam 34 is provided with a shoulder 80 and pivoted to the frame plate 10 is a dog 81 normally held in the path of the shoulder by the spring 35. This spring, as heretofore stated, acts on the latch lever 37 and is anchored at one end of that lever and at the other end to the dog 81 and tends to hold each of these members against suitable stops secured to the frame plate. Mounted on the lever 72 is a pawl 82 normally held in the position shown in Fig. 2 by a spring 34, which tends to retain a pin 85 on the pawl against a portion of the lever 72.

The lever 72 is so timed with relation to the drums that it is swinging in counterclockwise direction when the gap of the master drum is passing the blanket drum. In the latter portion of this movement the pawl 82 acts on the dog 81 and swings the lower end thereof out of the path of the shoulder 80, allowing the hand lever 32 to turn the eccentric shaft into the position shown in Fig. 3, before the gap has passed the blanket, so that the blanket is in position to engage the master sheet as the rotation continues and brings the master sheet by rolling action into juxtaposition with the blanket.

In the operation of the machine, when the operator desires to cause the engagement of the master with the blanket he grasps the handle 32 and starts to turn it in the clockwise direction. If the gap in the master drum happens to be opposite the blanket at this time the dog 81 will leave the cam 34 free to move into position shown in Fig. 3. However, usually some other portion of the master sheet will be opposite the blanket when the operator starts to turn the handle 32 and hence the shoulder 80 will engage the dog 81 and the turning will be stopped before the blanket is contacting with the master. The operator then continues his manual pressure in the clockwise direction, against the action of the spring 39, until the dog 81 is freed from the shoulder, whereupon the completion of the movement of the hand lever actively positions the blanket ready to receive imprint of the image by rolling contact. On the back stroke of the lever 72 the pawl 82 clicks idly across the end of the dog 81, as allowed by the spring 34.

It will be noted that the arrangement is such

that the pawl will engage the dog 31 for a relatively short period of time, quickly sliding from the end of the dog and permitting the dog to swing into the active position shown in Fig. 2, before the gap in the drum has passed the point of contact of the two drums.

In building up the image on the offset blanket, repellent is first applied to the master sheet and then ink applied, while the offset blanket is held out of contact with the master sheet. Then the master drum may be rotated about four revolutions, retaining it still out of contact with the master sheet to build up the inked image on the master sheet without further application of repellent. Then by rotating the master drum about four more revolutions, with the ink and normal repellent mechanism 50 and 60 respectively in active engagement with the master sheet, and with the offset blanket in contact with the master sheet, a properly inked image will be produced on the offset blanket. These preliminary rotations of the master drum 26 may be produced by power, by turning the motor switch off and on, or by a hand wheel provided on some member rotating with the drum. Such wheel is indicated at 27 in Fig. 1 as being on the master drum shaft 21.

After the image has been properly built up on the blanket cylinder, and the motor is running to drive the various parts, it is only necessary to feed sheets to the bite of the blanket and platen drums to effect printing. The sheets to be printed are fed from the suitable tray 97 carried by the frame of the machine and projecting at the forward end thereof and adapted to carry a number of sheets with their edges fanned out so that they can be manually shoved one after another toward the printing machine.

While the control of the sheet feed is no part of the invention of this application, it is shown in Fig. 1, and may be briefly described as follows: There is provided a lower feed roller 101, and a coacting upper roller 102. Each of these rollers is made in two longitudinally spaced sections mounted on suitable shafts. Behind the line of contact of the two feed rollers is a stop finger 103 mounted on a pivoted bar 104 and counterweighted by a forwardly extending plate 105. The shaft of the upper feed roller 102 is journaled in a yoke frame 106 which is pivoted at 107 and carries a roller 108 which coacts with a cam 109 secured to the offset drum (Figs. 1 and 5). This cam for the most part is concentric as shown in Fig. 1 and by acting on the roller 108 maintains the upper feed roller out of contact with the lower feed roller and allows the counterweighted stop fingers to stand in the position shown in Fig. 1, thus preventing the shoving of the paper to printing position.

The paper is shoved forwardly manually during the period of separation of the upper and lower feed rollers under a suitable downwardly inclined guide 110 until it abuts the fingers 103. Now when the flattened portion of the cam 109 comes opposite the roller 108 this frees that roller and the upper feed roller 102 descends by gravity into engagement with the lower feed roller. At the same time, a pin 111 depending from the front portion of the pivoted yoke engages a lever 112 on the bar 104 carrying the stop fingers. This swings the stop fingers down to idle position, out of the path of the sheet. The lowering of the upper feed roll not only removes the stop fingers from the path of the sheet but also, because of the rotation of the lower feed roll, causes the sheet to be

fed forward between suitable guides into the bite of the offset blanket and platen.

The paper feed rolls are held separated while the master sheet is being prepared for the printing operation. To accomplish this use is made of the latch mechanism 34, 35, 36, 37 which is used to separate the offset and master drums during the period of preparation, as heretofore described. A roller 115 is mounted on the yoke 106 which carries the upper feed roll 102. When the offset drum shaft is in its idle position (Fig. 2) this roller is engaged by the cam 34 in such manner as to swing the yoke 106 to raise the upper feed roll 102.

15 The cam 34, it will be seen, performs three functions; it holds the feed rollers separate when the drums are idle; it prevents the positioning of the blanket drum except when the gap of the master drum is opposite it, and it retains the blanket drum in its active position when it has been so placed until released by the actuation of the finger member 38 on the latch 37.

20 While any suitable gearing may be used to rotate the various rotatable parts of the machine, 25 I will, for completeness, describe the particular gearing so far as it appears in the drawings. As shown in Fig. 1 the motor 16 by its belt 17 operates a large sheave 18 which is on a shaft 120 rigidly carrying a pinion 121. This pinion is shown as 30 meshing with the gear 122 on a stub shaft 123 carrying the pinion 128 (Fig. 6). The pinion 128 meshes with a pinion 124, which meshes with a gear 125 on the master drum 26. The pinion 124 also is shown as meshing with a gear 127 on the 35 shaft of the distributing roll 54 of the inking system.

The gear 125 on the master drum, which has a pitch circle corresponding to the periphery of the mounted master sheet, is shown as meshing 40 with an equal size gear 130 (Fig. 6) on the offset drum. This latter gear meshes with a gear 131 on the platen shaft 41.

I claim:

45 1. In an offset printing machine including a frame having a master drum and a transfer drum, means to rotate said drums in timed relation with each other, one of said drums being mounted for rotation on a shaft eccentrically mounted in the frame to move such drum into and out of contact with the other drum, means constantly tending to separate said drums, a latch normally acting to retain said drums in a contacting relation and manually releasable at any time during the revolution of the drums whereby the drums may be separated at any time, manually operated means to reset said drums in a contacting relation, means including a latch plate on said shaft to cooperate with the latch, resilient means to hold the latch in a latching position, and a second latch to cooperate with the latch plate to latch the shaft in a drum separating position against the action of the resetting means, and means operating in timed relation with the rotation of the drum to release said last named latch at a predetermined point in the revolution of the master drum and hold the latch released for a predetermined portion of the cycle of revolution of the drum to thereby prevent resetting of said drums except during a predetermined portion of the cycle of revolution of the master drum and yet permit separation of said drums at any time during the cycle of revolution of said drums.

50 2. An offset printing machine according to claim 1 having an arm integrally carried by the

manually releasable latch and accessible to the operator, a pair of spaced abutments on the latch plate to engage respective latches, resilient means tending to move the second named latch into the path of its respective abutment, an operating member accessible to the operator manually operable to reset the drums and mounted on the eccentric shaft, a swinging arm operating in timed relation with the rotation of the drums, and a pawl carried on said arm to engage the second named latch to move it out of engagement with its abutment whereupon the drums may be reset manually.

3. An offset printing machine according to claim 2 having a sheet feeding mechanism to feed sheets to be printed to the offset drum, and means carried by said latch plate and coacting with said mechanism to cause said mechanism to fail to feed a sheet when the drums are separated.

4. An offset printing machine according to claim 3 wherein the sheet feeding mechanism includes a pair of feed rolls, a pair of pivoted arms, one of said rolls being mounted in said arms for movement toward and from the other roll, means normally tending to hold said rolls in a coacting relation, and means carried by said arms and adapted to be engaged by said latch plate to separate said rolls when the drums separate.

5. In an offset printing machine including a frame having a master drum and a transfer drum, a platen, means to rotate said drums in timed relation with each other, one of said drums being mounted for movement toward and from the other drum whereby the drums may be brought into contact with each other or separated, means constantly tending to separate said drums, a manually releasable latch normally acting to retain said drums in a contacting relation, manually operable means to reset said drums in a contacting relation, releasable means to prevent resetting of said drums, means to release said last named releasable means during a predetermined portion of the cycle of rotation of the master drum and yet permit separation of said drums at any time during the cycle of revolution of said drums, consequent upon the release of said releasable latch a pair of feed rolls to feed sheets to the bite of said platen and offset drum, one of said rolls being movably mounted, means constantly tending to retain said rolls in a coacting relation, and means responsive to the movement of the movable drum to a separated position to move said movable roll away from its coacting roll.

6. In an offset printing machine, a frame having a master drum and a transfer drum and a platen roller, means to rotate said drums and roller in timed relation with each other, said transfer drum being rotatably mounted on a shaft eccentrically journaled in said frame whereby rotation of said shaft moves said transfer drum into and out of contact with said master drum, a latch plate secured to said shaft, means to bias said shaft in a position with the transfer drum out of contact with the master drum, a latch member coacting with said plate to oppose the action of said biasing means and maintain said shaft in a position with the drum in contact, said latch member being manually releasable at any time during the operation of said drums, a manually operable means on said shaft for turning said shaft against the action of said biasing means into cooperation with said latch, a second latch to engage said latch plate

5 and restrain movement of said shaft by the operation of said manually operable means, means to bias said latches for engagement with said latch plate, a lever pivoted to said frame, means to oscillate said lever once for each revolution of said drums, a pawl pivoted to said lever and adapted to release said second named latch only at a predetermined point in the rotative movement of said drums.

7. A printing machine according to claim 6 having a pair of coacting feed rolls to feed sheets to the bite of said transfer drum and platen roller, a pair of arms pivoted to said frame intermediate their ends, one of said rolls being rotatably mounted in said arms adjacent one end thereof and extending therebetween, a roller mounted on the opposite end of one of said arms and adapted to engage the periphery of said latch plate, and wherein said latch plate is provided with a cam portion to engage said roller and move said arms to separate said feed rolls when the cam plate moves out of engagement with said first named latch.

8. In an offset printing machine, a frame having a master drum and a transfer drum, means to rotate said drums in timed relation with each other, said transfer drum being rotatably mounted on a shaft eccentrically journaled in the frame to move said transfer drum into and out of contact with said master drum, a latch plate secured to said shaft, resilient means interposed between said plate and frame to bias said shaft to a position with the transfer drum out of contact with the master drum, a latch member being pivoted to said frame and coacting with said plate to retain said plate and shaft in position with the transfer drum in contact with the master drum, manually operable means on said shaft for turning said shaft against the action of said spring and into cooperation with said latch, a second latch pivoted to said frame and coacting with said latch plate to restrain operation of said manually operable means, resilient means interconnecting said latches to bias them for engagement with said latch plate, a lever pivoted to said frame, means to oscillate said lever once for each revolution of said drums, a pawl pivoted to said lever and adapted to swing said second named latch momentarily to a released position at a predetermined point in the rotative movement of said drums.

9. In an offset printing machine, a frame having a master drum having a printing plate positioned on a portion of its periphery and having a portion of its periphery extending substantially from end to end thereof uncovered by said printing plate, a transfer drum and a platen roller 60 together with means to rotate said drums and roller in timed relation with each other, said transfer drum being rotatably mounted on a shaft eccentrically journaled in the frame whereby rotation of said shaft moves said transfer drum into and out of contact with said master drum, a member secured to said shaft, a spring interposed between said member and said frame to bias said shaft for movement to a position with the transfer drum out of contact with the master drum, a manually releasable latch pivoted to said frame and engaging said member plate to retain said shaft in a position with the transfer drum in contact with the master drum, said latch being manually releasable at any time during the rotation of said drums, manually

operable means for turning said shaft against the action of said spring and said member into latching engagement with said latch, a second releasable latch pivoted to said frame and adapted to engage said member and prevent movement of said shaft by preventing the operation of said manually operable means, resilient means to bias said latches for engagement with said member, a lever pivoted to said frame, means carried by one of said drums to swing said lever back and forth once during each revolution of said drums, and means on said lever to momentarily move said second named latch momentarily to a released position only when the uncovered portion of the master drum is in position to coat 15 with the transfer drum.

EDWARD J. JANKE.
